UNITED STATES PATENT OFFICE

109,700

DESIGN FOR A COAT

Samuel H. Dick, New York, N. Y.

Application April 13, 1938, Serial No. 76,463

Term of patent 3½ years

To all whom it may concern:

Be it known that I, Samuel H. Dick, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front perspective view of a coat showing my new design.

Fig. 2 is a rear view thereof.

The dotted lines on the sleeves represent quilting.

My design is characterized by the sleeves, embroidered with the specific quilted floral elements shown, in combination with the specific coat as shown.

The flower on the shoulder of the coat is permanently attached.

I claim:

The ornamental design for a coat substantially as shown and described.

SAMUEL H. DICK.
